(57) **CLAIM**

The ornamental design for a ladder quick connect base unit, as shown and described.

DESCRIPTION

FIG. 1 is a rear perspective view of a ladder quick connect base unit showing my new design;

FIG. 2 is a front perspective view of the base unit illustrated in FIG. 1;

FIG. 3 is a back view of the base unit illustrated in FIG. 1; FIG. 4 is front view of the base unit illustrated in FIG. 1, FIG. 5 is a top view of the base unit illustrated in FIG. 1; FIG. 6 is a bottom view of the base unit illustrated in FIG. 1;

FIG. 7 is a right side view of the base unit illustrated in FIG. 1;

FIG. 8 is a left side view of the base unit illustrated in FIG. 1;

FIG. 9 is a perspective in use view of the base unit illustrated in FIG. 1; and,

FIG. 10 a side perspective in use view of the base unit illustrated in FIG. 9.

The dotted lines in FIGS. 1 through 10 are for the purpose of illustrating portions of the ladder quick connect base unit and form no part of the claimed design. The broken lines showing a portion of a ladder and flooring in FIGS. 9 and 10 are for the purpose of illustrating environment and form no part of the claimed design.
